CONTROL MECHANISM

Edward P. Bullard, III, Fairfield, Conn., assignor
to The Bullard Company, a corporation of
Connecticut

Application August 23, 1940, Serial No. 353,935

43 Claims. (Cl. 192—142)

This invention relates to control mechanisms, and particularly to an automatic control mechanism for apparatus including one or more members each adapted to be moved in either direction along one or more paths at a plurality of speeds.

The principal object of this invention is to provide apparatus including one or more members adapted to be moved in either direction along separate paths at a plurality of speeds by means, the activity of which is initiated by a source of power separate from that incident to, but which source is rendered effective by the motion of said members.

Other objects include, the provision of an automatic control mechanism for apparatus including one or more members adapted to be moved along separate paths at various rates, wherein the control is adapted to be set for re-producing every direction and rate, or sequence of directions and rates of movement of said members that can be accomplished with the apparatus by an individual; and the provision of a plurality of appliances each including one or more members adapted to be moved along separate paths at a plurality of rates by means, the activity of which is initiated by a source of power separate from that incident to, but which source is rendered effective by the motion of said members, and in which any member of any of the appliances is capable of rendering effective any of said separate sources of power.

The above, as well as other objects and novel features of the invention, will become apparent from the following specification and accompanying drawings, in which:

Figure 1 is a diagrammatic representation of apparatus embodying the principles of the invention;

Figure 2 is an end elevational view, looking from left to right along line 2—2 of Figure 1;

Figure 3 is an electrical circuit for three sets of apparatus similar to that of Fig. 1, arranged in cooperative relationship;

Figure 4 is an elevational view taken substantially along line 4—4 of Fig. 1;

Figure 5 is an enlarged elevational view looking from right to left along line 5—5 of Fig. 1; and

Figure 6 is a diagram of a cycle of movement of a member controlled by apparatus embodying the principles of the invention.

The principles of the invention have been shown diagrammatically in their simplest form, and they will be described without regard to

any specific machine because they can be applied with equal facility to any type of apparatus including one or more members adapted to be moved along one or more paths.

Referring to Fig. 1, a member 10 is adapted to be moved along slide bearings 11 formed in a member 12; the member 12 is adapted to be moved along ways 13 on a member 14; and the member 14 is adapted to be moved along a line 15 at right angles to the plane of Fig. 1. Accordingly, the member 10 may be moved in three separate directions at right angles to each other and, therefore, to any point in space by combining its motion in the three directions.

Referring to Figs. 1 and 2, the member 12 is adapted to be moved along the ways 13 by the rotation of a screw 15 that is threaded into a boss 16 on the back of member 12. The member 10 is adapted to be moved along the slide bearings 11 by the rotation of a splined shaft 17 on which a spur gear 18 is adapted to slide and to be rotated upon rotation of shaft 17. The width of a groove 19 in slide 10 (Fig. 2), is equal to the thickness of the gear 18 so that the latter is moved with members 10 and 12 along ways 13. The gear is adapted to mesh with a rack 20 fixed to the back of the member 10, and located at the bottom of the groove 19. The member 14 is provided with an internally-threaded boss 21 (Fig. 2) integral with member 14, extending from its underside and into which a screw 22 is threaded. Accordingly, rotation of screw 15 will move the member 10 and the member 12 along the ways 13, rotation of the splined shaft 17 will move the member 10 along the bearings 11, and rotation of the screw 22 will move the entire assembly at right angles to the plane of Fig. 1.

Rotation of the screws 15, 22 and shaft 17 is effected by a transmission T driven by a variable-speed motor 23. The transmission comprises three pairs of oppositely rotatable gears 24, 25; 26, 27; and 28, 29. The shaft of motor 23 supports a relatively long gear 30 that meshes with gears 24 and 26. An additional relatively long gear 31, on a stub shaft parallel with the shaft of motor 23, is adapted to partially overlap gear 30 and to mesh therewith. Gears 25 and 27 are adapted to mesh with the gear 31. Since gear 31 is rotated by gear 30, gears 25 and 27 are rotated oppositely to that of gears 24 and 26. The shaft of motor 23 likewise supports an additional relatively long gear 32 that meshes with gear 28. A gear 33, similarly mounted as gear 31, meshes with gear 32, and also with gear 29. The units including gears 24, 25; 26, 27 and 28, 29

comprise separate means for moving the member 10 along its three paths of motion.

Referring to Figs. 1 and 4, shaft 17 and screw 15 are provided with bevel gears 34, 35 that mesh with bevel gears 36, 37 splined to vertically-disposed shafts 38, 39, respectively. The gears 36, 37 are adapted to slide along shafts 38, 39, remaining in mesh with gears 34, 35 as the assembly is moved at right angles to the plane of Fig. 1. Additional bevel gears 40, 41 are fixed to the upper ends of shafts 38, 39 and they mesh with bevel gears 42, 43 keyed to shafts 44, 45, respectively. The shafts 44, 45 are adapted to support gears 24, 25 and 26, 27 for free rotation. Clutches 46, 47 are splined to shafts 44, 45, respectively, and they are provided with teeth that are adapted to engage corresponding teeth on the adjacent faces of gears 24, 25 and 26, 27, respectively. Accordingly, shifting clutches 46, 47 will effect the rotation of splined shaft 17 and screw 15 in forward and reverse directions.

A bevel gear 48 (Figs. 1 and 2) is keyed to the screw 22 and it meshes with a bevel gear 49 on one end of a shaft 50. Another bevel gear 51 keyed to the opposite end of shaft 50 meshes with a bevel gear 52 keyed to one end of a shaft 53. A bevel gear 54 on the opposite end of shaft 53 meshes with a bevel gear 55 keyed to one end of a shaft 56. A bevel gear 57 on the opposite end of shaft 56 meshes with a bevel gear 58 keyed to a shaft 59 on which gears 28, 29 are mounted for free rotation. A clutch 60 is splined to shaft 59 between gears 28, 29 and it is provided with teeth that are adapted to mesh with corresponding teeth on the adjacent faces of gears 28, 29. Accordingly, shifting clutch 60 will effect the rotation of screw 22 in a forward and reverse direction causing the assembly including members 10, 12 and 14 to be moved along a path at right angles to the plane of Fig. 1.

The clutches 46, 47 and 60 may be shifted into and out of engagement with the gears 24, 25; 26, 27 and 28, 29 by any automatic means such as electromotive means, fluid-operated means, etc. Although these clutches may be moved by any automatic means, they are shown, and will be described as being shifted by fluid-operated means. A shifting arm 61, adapted to engage a groove in the clutch 46, is fixed to a pull-rod 62. The opposite end of pull-rod 62 is fixed to a piston 63 within a cylinder 64. A stationary frame member 65 is provided with a passage that is bored, counterbored and threaded. The pull rod 62 extends through the passage in member 65, and an adjustable gland 66 on rod 62 is threaded into one end of said passage forming a chamber with the end of the counterbored portion thereof. Collars 67, loose on rod 62, are positioned within the chamber, and a preloaded compression spring 68 is located between collars 67 urging them against opposite ends of said chamber. The rod 62 is provided with reduced portions, one of which abuts the one collar 67 and the other providing means for threading a nut 69 thereon into abutting relation with the other collar 67. The construction and arrangement are such that the spring 68 normally urges the clutch 46 into its neutral position.

The cylinder 64 is adapted to be supplied with fluid under pressure through a valve body V having valves 70 and 71. A source of fluid under pressure is adapted to be directed through a line 72 into the valve body V, thence through a port 73 to both valves 70 and 71. The valves 70

and 71 communicate with an exhaust line 74 through an additional port 75 in the valve body V.

The right-hand side of cylinder 64 is connected to the valve body V by a line 76, while the left-hand side of said cylinder is connected to said body by a line 77. The valves 70 and 71 are normally urged downwardly by springs 78 and 79, and the construction of these valves is such that while in their downward position, the opposite sides of the piston 63 are in communication with the exhaust passage 74 through the port 75, and spring 68 centralizes the piston 63 in cylinder 64, thereby neutralizing clutch 46. Upon movement of either valve 70 or 71 to its upper limit, against the action of spring 78 or 79, communication is established between the piston 63 and the supply passage 72 through the port 73 and the lines 76 or 77. Such upward movement of valves 70 and 71 cuts off communication between exhaust port 75 and lines 76 and 77.

The clutch 47 is likewise provided with a shifting rod 82, and a pull-rod 83 connected to a piston 84 within a cylinder 85. The clutch 47 is resiliently urged to a neutral position by a spring 86 in the same manner that spring 68 tends to neutralize clutch 46. The right and left sides of cylinder 85 are connected to the valve body V by lines 88 and 89, respectively. A pair of valves 90, 91 is provided in the valve body V for supplying fluid under pressure to, and exhausting it from the cylinder 85 in the same manner that valves 70 and 71 control the supply of fluid to, and exhaust it from the cylinder 64.

The clutch 60 is also provided with a shifting rod 92 and a pull rod 93 connected to a piston 94 within a cylinder 95. The clutch 60 is resiliently urged to a neutral position by a spring 96 in the same manner that spring 68 tends to neutralize clutch 46. The right and left sides of cylinder 95 are connected to the valve body V by lines 98 and 99, respectively. An additional pair of valves 100, 101 is provided in the valve body V for supplying fluid under pressure to, and exhausting it from the cylinder 95 in the same manner that valves 70 and 71 control the supply of fluid to, and exhaust it from the cylinder 64.

The valves 70, 71, 90, 91, 100 and 101 are adapted selectively to be moved to their upper position for controlling the shifting of the clutches 46, 47 and 60 in either direction and in accordance with any predetermined order. This means comprises a movable member 102 which, in the embodiment disclosed, is shown as a drum adapted to be rotated on the shaft 102' in a step-by-step fashion. The drum 102 is provided with circumferential T-slots 103 adapted adjustably to support dogs 104 that cooperate with the stems of valves 70, 71, 90, 91, 100 and 101 to raise the valves and thereby selectively effect shifting of the clutches 46, 47 and 60. A disc 107, arranged to be moved with drum 102, is provided with adjustable means for selectively actuating a variable-resistance X connected in series with the motor 23 for changing the rate at which the transmission T is operated, and consequently the rate at which members 10, 12 and 14 are moved along their respective paths. Referring to Fig. 5, the disc 107 includes a plurality of radially-disposed series of openings, equal in number to that of the step-by-step positions of the drum 102. Abutments 107₁ are adapted to be mounted selectively on the disc 107 for cooperation with a lever 108 that is resiliently urged into engagement with said abutments. The lever 108 in-

cludes, at its one end, a contact member 108 that is adapted to slide over the contacts of the variable-resistance X.

The step-by-step indexing of the drum 102 and disc 107 is adapted to be effected by any suitable means which, upon being started, will perform one indexing movement of the drum 102 and then remain inactive until re-started at a later time. In the embodiment disclosed, the means employed to index drum 102 is independent of the force required to move member 10, but is rendered effective in response to the motion of member 10. One form of means for effecting the step-by-step indexing of the drum 102 is shown as a motor 105 adapted to drive a crank 106 through a single revolution and then to stop until subsequently re-started. The starting and stopping of the motor 105 is effected by a cam-operated electrical circuit maker and breaker to be described later. The crank 106 is provided with a roll adapted to pass into and out of a plurality of radial slots (Fig. 3) formed in a member 109 that rotates with the drum 102 and the disc 107, thereby to give a Geneva stop motion to said drum and disc. The number of radial slots may vary widely in any given design. During each index movement, the drum 102 is turned through a definite number of degrees. In order to facilitate the setting of the dogs 104 during a set-up period, they may be provided with an index line adapted to register with lines 104' on drum 102, which latter are spaced about drum 102 a number of degrees equal to that which drum 102 is moved during each index movement.

In the present embodiment of the invention, the motor 105 is adapted to be started in response to the position the member 10 may assume along any of its paths of travel. A movable member, preferably a drum 110, is located adjacent to, and parallel with the shaft 44. The drum 110 is provided with a groove 111, in which a roller of a switch-contacting element 112 of a switch 113 is adapted to seat when the switch is open. The drum 110 is adapted to be moved axially in either direction to effect closing of the switch 113, which is connected in series with the motor 105. The drum 110 is fixed to a shaft 114 that is adapted to be mounted for slight axial movement, and to extend within a bored, counterbored and threaded passage in a stationary frame member 115. A gland 116 on the shaft 114 is threaded into the passage in member 115, forming a chamber with the counterbored portion thereof. Collars 117, loose on shaft 114, are positioned within the chamber, and a preloaded compression spring 118 is located therebetween, urging them against opposite ends of said chamber. The shaft 114 is provided with a reduced portion forming a shoulder that abuts one of the collars 117, and a nut is threaded onto the end of shaft 114 in abutting relation with the other collar. The construction and arrangement of member 115 and its associated parts are such as to normally position the drum 110 axially whereby the roller on member 112 of switch 113 seats within the groove 111. Accordingly, slight axial movement of drum 110 in either direction will close switch 113, starting motor 105 thereby effecting a single indexing of drum 102.

Slight axial movement of the drum 110 is adapted to be effected in response to the position member 10 may assume along the path defined by the bearings 11. Accordingly, shaft 44 is provided with a screw thread 119 on which a non-rotat-

able axially-movable nut 120 is mounted. The threads 119 are of such pitch that upon rotation of shafts 44 and 17, the movement of nut 120 will be proportional to the movement of member 10 along bearings 11. The drum 110 is provided with axially-extending circumferentially-disposed T-slots 121 in which dogs 122 are adjustably located. A finger 123 on the nut 120 is adapted to engage dogs 122 to effect movement of the drum 110.

A drum 124, similar to drum 110, is mounted adjacent to, and parallel with the shaft 45 in the same manner that drum 110 is mounted with respect to shaft 44. The shaft 45 is provided with a thread 125 on which a non-rotatable nut 126 is mounted that moves axially in proportion to the movement of members 10 and 12 along the ways 13 of member 14. The drum 124 is provided with slots 127 within which axially-adjustable dogs 128 are mounted for cooperation with a finger 129 of the nut 126 in the same way that dogs 122 cooperate with finger 123 of nut 120. A switch 130, connected in parallel with switch 113, is adapted to be closed upon slight axial movement of drum 124, all in the manner as described in connection with the closing of switch 113 by the axial movement of drum 110.

A drum 131, similar to drum 110, is mounted adjacent to, and parallel with the shaft 53 in the same manner that drum 110 is mounted with respect to shaft 44. The shaft 53 also is provided with a thread 132 on which a non-rotatable nut 133 is mounted that moves axially in proportion to the movement of the member 14 on the screw 22. The drum 131 is provided with slots 134 within which axially-adjustable dogs 135 are mounted for cooperation with a finger 136 of the nut 133 in the same way that dogs 122 cooperate with finger 123 of nut 120. An additional switch 137, connected in parallel with switches 113 and 130, is adapted to be closed upon slight axial movement of drum 131, all in the manner as previously described in connection with the closing of switch 113 by the axial movement of drum 110.

The drums 102, 110, 124 and 131 are geared together through spur gears 138, 139, 140, 141, 142, 143 and 144. Gear 138 is mounted for rotation with drum 102 while gears 139, 142 and 144 are splined to shaft 114 and the shafts on which drums 124 and 131 are mounted, respectively. Gears 140, 141 and 143 are idle gears. This construction causes drums 110, 124 and 131 to be indexed with the function-selecting drum 102 so that the dogs 122, 128 or 135 which may be engaged by nuts 120, 126, or 133, to cause indexing of drum 102, are moved clear of said nuts, thereby permitting free movement of the nuts in either direction across drums 110, 124 or 131 until they abut other dogs 122, 128 or 135 in the next succeeding slots 121, 127 or 134 of said drums to initiate the next succeeding indexing of drum 102. Immediately upon the indexing of drums 110, 124, 131 they are returned by the spring 118 of drum 110, and the corresponding springs for drums 124 and 131 to a normal position causing switches 113, 130 or 137 to be opened. In order to insure a complete single revolution of motor 105 before stopping, a switch 145 is connected in series with motor 105, and in parallel with switches 113, 130, 137. A cam 146 is fixed to the shaft of motor 105, and its contour is such that switch 145 is open while the motor 105 is at rest, but when, upon closing of any of the switches 113,

138 or 137, the motor 105 starts, switch 145 also closes and remains closed sufficiently long to insure a single complete revolution of crank 106. The drums 102, 110, 124 and 131 are adapted to be pre-set by the operator each time it is desired to produce a different cycle of operation of member 10. This pre-setting of said drums is to be distinguished from the designing of certain types of automatic machinery in which a pre-determined fixed cycle of operation is built into the machine.

By virtue of the adjustable nature of the dogs 104, 122, 128, 135 and abutments 107 on drums 102, 110, 124, 131 and disc 107, respectively, a substantially limitless number of different cycles of operations of member 10 may be performed, and the number of changes in the direction and rate of movement of member 10 within each cycle will be limited only by the number of index positions these drums may assume. Since only a slight amount of motion is required of the drums 102, 110, 124, 131 and disc 107 in moving dogs 104, 122, 128, 135 and abutments 107 into and out of co-operating position with the stems of the valves for clutches 46, 47, 60, the fingers 123, 129, 136, and lever 108, respectively, it is evident that a great number of index positions of drums 102, 110, 124 and 131 may be provided with drums of practical size, and that a correspondingly large number of directions, rates, times of starting and stopping of motions of the member 10 may be accomplished in any desired cycle. Additionally, since each new direction, or rate of movement of member 10, is selected only upon the conclusion of the last preceding motion of the member, it is evident that any error that might be involved in initially setting the apparatus will not be accumulative. Furthermore, since each change in direction or rate of motion of the member 10 is initiated by indexing the drum 102, and drums 110, 124 and 131 are indexed with drum 102 whereby a nut 128, 126 or 133 cooperates with a selectively-positioned dog 122, 128 or 135 in a single slot 121, 127 or 134 for each such change in direction or rate of motion, it is evident that within each cycle of operation of member 10, said member may be moved throughout different overlapping strokes along the same path without affecting the setting of the apparatus for repeating the cycle of operation.

From the foregoing it is evident that this invention provides means for moving a member along one or more paths a relatively great number of times within a cycle of operation and for selecting the path, direction and/or rate of each movement of said member within said cycle. This invention also provides means for moving one or more members in either direction along one or more paths at a plurality of speeds to perform various cycles of operation wherein each cycle may include a plurality of sub-cycles. Such a sub-cycle of operation may be defined as a plurality of motions of a member at one or more speeds along one or more paths, starting from and substantially returning to a given point. Although a cycle of operation may not include sub-cycles of the above defined type, those which do include them may be defined as the repetition of identical groups of sub-cycles of which at least two sub-cycles are different.

The longitudinally-extending, circumferentially-disposed lines 104' on drum 102 comprise portions each of which is adapted adjustably to be set for causing member 10 to produce any function of which it is capable. The drums 110,

124 and 131 include longitudinally extending portions 121, 127 and 134, one for each of the portions 104' on drum 102 for controlling the duration of the function set up on the corresponding portion 104'. The gears 138, 139, 140, 141, 142, 143 and 144 maintain all of these portions in exact phase relation at all times.

Operation

10 To better illustrate the capabilities of the apparatus shown in Fig. 1, the initial setting of the apparatus will be described for repeatedly performing a relatively simple cycle of operation of member 10 at a constant rate of motion. Of course, it is to be understood that the cycle may include any number or sequence of the directions and rates of movement of which the member 10 is capable. Furthermore, the setting of the apparatus for any other cycle, including any number of directions and rates of movement of member 10 may be accomplished in substantially the same way.

20 Referring to Fig. 6, assume that it is desired to move member 10 from a starting point A along the x-axis to B, thence along the y-axis to C (the x and y axes being in the same plane), thence along the z-axis to D (the z axis being in a different plane than the axes x and y), and back through space to substantially the starting point A; and that it is then desired to move member 10 from the starting point A along the x-axis to E, thence along the y-axis to F, thence along the z-axis to G, and back through space to substantially the starting point A.

25 Referring to Fig. 1, handwheels 147, 148 and 149 may be fixed to the shafts 44, 45 and 53 for facilitating the initial setting of the control mechanism. With the member 10 at the starting point, the motor 23 at rest, and the valves 70, 71, 90, 91, 100 and 101 in their lower position insuring that clutches 46, 47 and 60 are in neutral, the handwheel 148 is rotated in a direction and an amount sufficient to move member 10 along the x-axis (Fig. 6) from A to B, and a dog 128 in a slot 127 adjacent nut 126 is moved into engagement with the finger 129. A complementary movement of one of the dogs 104 on drum 102 must be made so that upon indexing the drum, valve 100 will be raised to connect the right side of cylinder 95 with the supply line 72, and all other dogs 104 are so adjusted as not to cooperate with the other valves when the drum 102 is indexed. Accordingly, valve 101 as well as all other valves except valve 100 remains in their lower positions thereby connecting the left side of cylinder 95 to the exhaust line 74. The drum 102 is then indexed, thereby locating the next succeeding slots 121, 127 and 134 of cylinders 110, 124 and 131 adjacent the shafts 44, 45 and 53. The handwheel 149 is then rotated in a direction and an amount necessary to cause member 10 to move from point B along the y-axis to C, and a dog 135 is positioned in the slot 134 adjacent the nut 133 so that it contacts finger 136 thereof. A complementary movement of another dog 104 must be made in the slot 103 of drum 102, which slot is in line with valve 70, such that upon the next indexing of drum 102, valve 70 will be raised to connect the right side of cylinder 64 with the inlet 72. The remaining dogs 104 that have not been set are so adjusted as not to cooperate with the other valves when the drum 102 is again indexed. Accordingly, valve 71 remains in its low position thereby connecting the left side of cylinder 64 to the exhaust line 74.

The drum 102 is again indexed to locate the next succeeding slots 121, 127 and 134 of drums 110, 124 and 131 adjacent shafts 44, 45 and 53. The handwheel 147 is rotated in a direction, and an amount sufficient to move the member 10 from point C along the z-axis to D, and a dog 122 is positioned to engage the finger 123 of nut 120. A complementary movement of dogs 104 on drum 102 must be made so that upon the next indexing of cylinder 102, they will raise valves 91, 101 and 71 thereby connecting the left-hand sides of cylinders 85, 95 and 64 to the supply line 72. The remaining un-set dogs 104 are so adjusted as not to cooperate with the valves 90, 100 and 70 when the drum 102 is again indexed whereby, upon such indexing of drum 102, the right-hand sides of cylinders 85, 95 and 64 are open to the exhaust line 74. The drum 102 is again indexed to locate the next succeeding slots 121, 127 and 134 of drums 110, 124 and 131 adjacent shafts 44, 45 and 53. Handwheels 147, 148 and 149 are rotated in a direction, and an amount sufficient to cause member 10 to move from point D substantially to its starting point A, closing the path of its movement. A dog 122, 128 or 135 is positioned to engage fingers 123, 129 or 136. A complementary movement of a dog 104 must then be made so that upon the next indexing of the drum 102 valve 90 will be raised to connect the right-hand side of cylinder 85 with the supply line 72. The remaining un-set dogs 104 are so adjusted as not to cooperate with the other valves when the drum 102 is again indexed whereby the left-hand side of cylinder 85 is open to the exhaust line 74. The handwheel 148 is again rotated in the direction and an amount necessary to move member 10 from point A along the x-axis to point E. The procedure of setting additional dogs 104, 122, 128, 135 on drums 102, 110, 124, 131 and rotating handwheels 147, 148, 149 in the correct directions and amounts to move member 10 from point E, along the y-axis to point F, thence along the z-axis to point G, and finally back through space substantially to the starting point A is effected in the same manner described above with respect to setting the control for causing member 10 to move successively about the path A-B-C-D-A.

With the apparatus set as above-described, it is only necessary to start motor 23 and to index drum 102 to cause member 10 repeatedly and successively to move automatically about the irregular paths defined by A-B-C-D-A; and A-E-F-G-A. The above procedure of setting a cycle of operation of the apparatus may be carried on indefinitely to include any number or sequence of the directions and/or rates of motion of which member 10 is capable. The number of different changes in direction and/or rates of motion in a cycle is only limited by the number of positions to which the drums 102, 110, 124 and 131 can be indexed, which number, as previously explained, may be very large with drums of practical size.

Any number of appliances, including one or more members such as member 10, may be cooperatively arranged to automatically perform a cycle in which may be produced any number or sequence of the directions and rates of motion of which the members are capable. That is to say, any of the plurality of control units may be started and stopped from the control drums 102 of any other unit.

Referring again to Fig. 1, wherein provision is made to control two additional appliances from

the appliance disclosed, T-shaped slots 150, 151 are provided in the circumference of drum 102 in which dogs 152, 153 may be selectively located for closing switches 154, 155 that are, respectively, in circuits for other motors 105₁ and 105₂ that index control drums 102₁ and 102₂ of appliances similar to the one shown in Fig. 1.

Referring to Fig. 3, an electrical circuit is disclosed for three appliances similar to that of Fig.

- 10 1 arranged in cooperative relation. As shown, the motors 105, 105₁ and 105₂ are adapted to index control drums 102, 102₁ and 102₂, respectively. Each of the circuits include six switches in parallel for starting the motors 105, 105₁ and 105₂. The circuit includes switches 113, 113₁, 113₂; 130, 130₁, 130₂; 137, 137₁, 137₂; and 145, 145₁, 145₂ arranged in the manner described with respect to the switches 113, 130, 137 and 145 of the appliance of Fig. 1. Additionally, the drum 102 contains means for closing switches 154 and 155 in the circuits for motors 105₁ and 105₂, respectively; drum 102₁ contains similar means for closing switches 154₁ and 155₁ in the circuits for motor 105 and 105₂, respectively; and drum 102₂ contains similar means for closing switches 154₂ and 155₂ in the circuits for motors 105 and 105₁, respectively.

From the foregoing description of Figs. 1 and 3, it is evident that a plurality of separate members is adapted repeatedly to perform various cycles of operation in each of which may be produced selectively a plurality of different directions and rates of motion of the members 10 in accordance with the setting of the dogs on the individual drums 102; that at any time during operation of one unit, the operation of another unit may be started; and that the units may be operated individually or simultaneously such that numerous functions may be performed by numerous members in accordance with any predetermined sequential order.

Although the various features of the control apparatus have been shown and described in detail to fully disclose one embodiment of the invention, it will be evident that numerous changes may be made in such details, and certain features may be used without others, without departing from the principles of the invention.

What is claimed is:

1. Apparatus comprising in combination, a plurality of appliances each including a member adapted to be moved along a path; means associated with each appliance for moving its member; separate means associated with each appliance adapted to be pre-set for controlling the member-moving means of said appliance to determine the direction of motion of its member; and means for initiating the activity of each of said pre-settable means in response to a preceding movement of any of said members.

2. Apparatus comprising in combination, a plurality of appliances each including a member adapted to be moved along a plurality of paths at a plurality of speeds; separate intermittently-movable means associated with each appliance and adapted to be pre-set for controlling the member-moving means thereof to determine the path and rate of movement of said member; and means for initiating the activity of each of said pre-settable means in response to a preceding movement of any of said members.

3. Apparatus comprising in combination, means adapted to be moved; a movable member for controlling the movement of said means; and an

element capable of a plurality of movements for initiating the movement of said control member, one of the movements of said movable element being synchronized with the movement of said control member, and another movement of said element being responsive to movement of said means and adapted to initiate the movement of said control member.

4. Apparatus comprising in combination, means adapted to be moved; a rotatable member for controlling the movement of said means; and an axially-movable rotatable element for initiating the rotation of said control member, the rotatable movement of said element being synchronized with the rotation of said control member, and the axial movement of said element being responsive to movement of said means.

5. Apparatus comprising in combination, means adapted to be moved; a movable member for controlling the movement of said means adapted to be indexed from one position to another; and an element adapted to be moved in a plurality of directions in response to movement of said means for initiating the indexing of said control member and adapted to be indexed with said control member.

6. Apparatus comprising in combination, means adapted to be moved; a rotatable member for controlling the movement of said means; means for indexing said control member from one position to another; and a plurality of elements axially movable in response to movement of said means for initiating the indexing of said control member and adapted to be indexed from one position to another with said control member.

7. Apparatus comprising in combination, a member adapted to be moved along a plurality of paths at a plurality of speeds; means for moving said member along said paths; force-exerting means for rendering said member-moving means effective; movable control means adapted selectively to actuate said force-exerting means for causing said member to move along any of said paths at any one of a plurality of speeds; and movable elements for initiating the movement of said control means in response to the position of said member along said paths, at least a portion of the movement of said elements being synchronized with the movement of said control means.

8. Apparatus comprising in combination, a member adapted to be moved in either direction along a path at a plurality of speeds for performing a cycle of operation that may include a plurality of sub-cycles; a rotatable control element having adjustable means for independently selecting the direction and rate of movement of said member within each sub-cycle; and means for indexing said control element from one position to another in response to a position said member may assume along said path, said means including separate adjustable means for each movement of said member, adapted to cooperate with said member at any point along its path of travel and to be indexed with said control element.

9. Apparatus comprising in combination, a member adapted to be moved along a plurality of paths at a plurality of speeds; variable-speed transmission means for moving said member along said paths at said plurality of speeds; adjustable means adapted to cooperate with said transmission means for selecting the paths and rates of

movement of said member; and means for each of said paths adapted to cooperate with means movable in proportion to the movement of said member at any point throughout the entire path of travel of said member for determining the starting and stopping of motion of said member.

10. Apparatus comprising in combination, a member adapted to be moved along a plurality of paths at a plurality of speeds; variable-speed transmission means for moving said member along said paths at said plurality of speeds; control means adapted to be indexed in a step-by-step manner and including selectively adjustable means for cooperating with said transmission for selecting the paths and rates of movement of said member; and means responsive to the movement of said member and adapted to be indexed with said control means for determining the distances said member moves along said paths.

11. Apparatus comprising in combination, a member; means for moving said member along a path for performing a cycle of operation that may include a plurality of sub-cycles; force-exerting means for controlling said member-moving means; means for independently selecting the direction of movement of said member within each sub-cycle; and a plurality of means adapted to engage means, movable in proportion to the movement of said member, at any point along the path of travel of said proportionally-movable means for rendering said selecting means effective, each of said plurality of means being adapted to be rendered ineffective relatively to said proportionally movable means substantially instantly after engagement therewith.

12. Apparatus comprising in combination, a member; means for moving said member along a plurality of paths; means for rendering said member-moving means effective; means for independently selecting the paths and directions of movement of said member along said paths; and an element for each of the paths along which said member is adapted to move including a plurality of means adapted to cooperate with means, movable in proportion to the movement of said member, at predetermined points along the path of travel of said proportionally-movable means for rendering said selecting means effective, each of said plurality of means being adapted to be rendered ineffective relatively to said proportionally movable means immediately after rendering said selective means effective.

13. Apparatus comprising, a member; means for moving said member along a plurality of paths; means for rendering said member-moving means effective; means for independently selecting the path, direction and rate of movement of said member; and a plurality of means adapted selectively to cooperate with means, movable in proportion to the movement of said member, for rendering said selecting means effective, each of said plurality of means being adapted to be rendered ineffective relatively to said proportionally movable means immediately after rendering said selecting means effective.

14. Apparatus comprising in combination, a member adapted to be moved along a plurality of paths; means for moving said member along said paths including driving means normally maintained in neutral; adjustable means for independently selecting a path and direction along which said member is to be moved including means for rendering active selected of said driving means; and means including an element for each of said plurality of paths adapted to simulate

the movement of said member along said paths for operating said selecting means only upon the substantial completion of the movement of said member in the preceding selected direction and along the preceding selected path.

15. Apparatus comprising in combination, a plurality of members each adapted to be moved along a plurality of paths at a plurality of speeds; means for moving said members along said paths; separate means for independently selecting a path, direction and rate of movement of each of said members; means for operating each of each selecting means to choose a succeeding path, direction and rate of movement for its member in response to the substantial completion of the movement of its member along a preceding selected path; and means associated with each of said selecting means for operating the other.

16. Variable-cycle apparatus comprising in combination, a member adapted to be moved in either direction along a path at a plurality of speeds a relatively great number of times within a cycle of operation; means for moving said member along said path at said speeds; means adapted selectively to be operated for controlling the operation of said member-moving means; pre-settable means adapted selectively to operate a plurality of means including selected of said control means to determine the direction and rate of each movement of said member within said cycle of operation; a source of power for operating said pre-settable means; and separate means for controlling successive movements of said member along said path, and responsive to the movement of said member at any point along its path of travel for determining when said source of power is to be rendered effective.

17. Apparatus comprising in combination, a member adapted to be moved in either direction along a path at any one of a plurality of speeds; means for moving said member along said path at said speeds; means adapted selectively to be operated for controlling the operation of said member-moving means; pre-settable means adapted selectively to operate a plurality of means including selected of said control means; a source of power for operating said pre-settable means; and separate means for controlling successive movements of said member along said path, and responsive to the movement of said member for operating an electric circuit to render effective said source of power.

18. Variable-cycle apparatus comprising in combination, a member adapted to be moved in either direction along a path at a plurality of speeds a relatively great number of times within a cycle of operation; means for moving said member along said path at said speeds; means adapted selectively to be operated for controlling the operation of said member-moving means; pre-settable means adapted selectively to operate a plurality of means including selected of said control means to determine the direction and rate of each movement of said member within said cycle of operation; means for indexing said pre-settable means from station to station; a source of power for indexing said pre-settable means; and separate means for controlling successive movements of said member along said path, and responsive to the movement of said member at any point along its path of travel for determining when said source of power is to be rendered effective.

19. Variable-cycle apparatus comprising in combination, a member adapted to be moved in

either direction along a path at a plurality of speeds a relatively great number of times within a cycle of operation; means for moving said member along said path at said speeds; means adapted selectively to be operated for controlling the operation of said member-moving means; pre-settable means adapted selectively to operate a plurality of means including selected of said control means to select the direction and rate of

10 each movement of said member within said cycle of operation; means for indexing said pre-settable means from station to station; a source of power for indexing said pre-settable means; means responsive to the movement of said member at any point along its path of travel for determining when said source of power is to be rendered effective; and means for indexing said determining means simultaneously with the indexing of said pre-settable means.

20. Apparatus comprising in combination, a member adapted to be moved in either direction along a plurality of paths at a plurality of speeds; means for moving said member along said paths at said plurality of speeds; common means adapted to be pre-set and adapted to be indexed from station to station for rendering effective said member-moving means for moving said member along any of said paths at any of said speeds; a source of power for indexing said common means; separate means for each path along which said member is adapted to be moved for determining when said source of power is to be rendered effective; and means for indexing said separate means simultaneously with the indexing of 35 said common means.

21. Apparatus comprising in combination, a member; a support; means for providing relative movement between said member and support; means for controlling the means that provides the 40 relative movement between said member and support; pre-settable means adapted to operate a plurality of means including selected of said control means; an additional source of power, separate from the power developed by the relative 45 movement between said member and support, for operating said pre-settable means; and separate means for controlling successive relative movements of said member and responsive to said relative movement at any point along the path thereof for determining when said additional source 50 of power is to be rendered effective.

22. Apparatus comprising in combination, a support; a member; means for providing a plurality of relative movements between said member and support along a plurality of paths at a plurality of speeds; means adapted to control said member-moving means for moving said member along said plurality of paths at any of said plurality of speeds; common means adapted 55 to be pre-set for operating selected of said controlling means; an additional source of power, separate from the power developed by the relative movement between said member and support, for operating said common means; and means for each path along which said relative movements are to be effected including separate means responsive to every such relative movement for determining when said additional source of power is to be rendered effective.

70 23. Apparatus comprising in combination, a support; a member; means for providing relative movement between said member and support along a plurality of paths at a plurality of speeds; means adapted to control said member-moving means for moving said member along any of

said paths at any of said plurality of speeds; common means adapted to be pre-set for operating selected of said controlling means; an additional source of power, separate from the power developed by the relative movement between said member and support, for operating said common means; and separate means for each path along which said relative movement is to be effected and responsive to said relative movement for operating an electric circuit to render effective said additional source of power.

24. Apparatus comprising in combination, a support; a member; means for providing relative movement between said member and support along a plurality of paths and at a plurality of speeds; means adapted to control said member-moving means for moving said member along any of said paths at any of said speeds; common means adapted to be pre-set for operating selected of said controlling means; a source of power, independent of the force required to effect the relative movement between said member and support for indexing said common means from station to station; separate means for each path along which said relative movement is to be effected for determining when said source of power is to be rendered effective; and means for indexing said separate means from station to station simultaneously with the indexing of said common means.

25. Apparatus comprising in combination, a plurality of appliances, each including a member adapted to be moved in either direction at a plurality of speeds along a plurality of paths; separate means connected to each of said members for moving them along said paths at said plurality of speeds; means adapted selectively to be operated for controlling said member-moving means; common pre-settable means associated with each appliance adapted selectively to operate a plurality of means including selected of the control means for its member-moving means; a source of power for each appliance, independent of the force required to move its member, for operating its common pre-settable means; and separate means responsive to each movement of the member of each appliance for determining when the source of power for its common pre-settable means is to be rendered effective.

26. Apparatus comprising in combination, a plurality of appliances, each including a member adapted to be moved in either direction at a plurality of speeds along a plurality of paths; separate means connected to each member for moving it along the paths of its appliance; means adapted selectively to be operated for controlling the member-moving means of each appliance; common pre-settable means associated with each appliance adapted selectively to operate a plurality of means including selected of the control means for its member-moving means; an additional source of power for each appliance, separate from that developed by the movement of its member, for operating its common pre-settable means; means responsive to the movement of the member of each appliance for determining when the additional source of power for its common pre-settable means is to be rendered effective; and means associated with the common pre-settable means for each of said appliances adapted selectively to render effective the additional source of power for every other appliance.

27. Apparatus comprising in combination, a member adapted to be moved in either direction along a path a relatively great number of times

within a cycle of operation; pre-settable means including means adapted successively to be moved from position to position for controlling the movement of said member; means movable in proportion to the movement of said member; and means for determining when said successively-movable means is to be moved including an element engageable with said proportionately movable means at any point along its path of travel and adapted instantly upon such engagement to be rendered ineffective relatively to said proportionately movable means.

28. Apparatus comprising in combination, a member adapted to be moved in either direction along a path; a control drum adapted to be pre-set and successively to be indexed from station to station for controlling the movement of said member; means movable in proportion to the movement of said member; and means for determining when said control drum is to be indexed including an element engageable with said movable means at any point along its path of travel and adapted instantly upon such engagement to be rendered ineffective relatively to said movable means.

29. Apparatus comprising in combination, a member adapted to be moved in either direction along a path; a control drum adapted to be pre-set and successively to be indexed from station to station for controlling the movement of said member; means movable in proportion to the movement of said member; means for determining when said control drum is to be indexed including a drum on which an element is adapted adjustably to be mounted, said element being engageable with said movable means at any point along its path of travel and adapted instantly upon such engagement to be moved out of cooperative alignment relatively to said movable means; and means for simultaneously indexing said control drum and the drum on which said element is mounted.

30. Apparatus comprising in combination, a member adapted to be moved in either direction along a path; pre-settable means including means adapted successively to be moved from position to position for controlling the movement of said member; a source of power for moving said successively-movable means; means movable in proportion to the movement of said member; and means for determining when said source of power is to be rendered effective including an element engageable with said proportionately movable means at any point along its path of travel and adapted instantly upon such engagement to be rendered ineffective relatively to said proportionately movable means.

31. Apparatus comprising in combination, a member adapted to be moved in either direction along a plurality of paths; pre-settable means including means adapted successively to be moved from position to position for controlling the movement of said member; separate means movable in proportion to the movement of said member along each of its paths of motion; and separate means for each of said paths for determining when said successively-movable means is to be moved, each including elements engageable with said separate movable means and adapted instantly upon such engagement to be rendered ineffective relatively to said separate movable means.

32. Apparatus comprising in combination, a member adapted to be moved in either direction along a plurality of paths; a control drum adapt-

ed to be pre-set and successively to be indexed from station to station for controlling the movement of said member; separate means adapted to be moved proportionally as said member moves along each of its paths of motion; separate drums for each of said paths on which elements are adapted adjustably to be mounted, for determining when said control drum is to be indexed, said elements being engageable with said separate movable means and adapted instantly upon such engagement to be moved out of cooperative position relatively to said movable means; and means for simultaneously indexing all of said drums.

33. Apparatus comprising in combination, a member adapted to be moved in either direction along a plurality of paths; common control means adapted to be pre-set including means adapted successively to be moved from position to position for controlling the movement of said member; a source of power, independent of the force required to move said member, for moving said successively-movable means; separate means for each path, movable in proportion to the movement of said member along said path; and means for determining when said source of power is to be rendered effective including elements for each path along which said member is adapted to be moved, the elements of each path being engageable with the proportionately movable means for that path and adapted instantly upon such engagement to be rendered ineffective relatively to said proportionately movable means.

34. Apparatus comprising in combination, a member adapted to be moved along a plurality of paths at a plurality of speeds; means for moving said member; means adapted to be pre-set for controlling said member-moving means to determine the path, direction and rate of motion of said member; a source of power separate from that developed by the movement of said member for intermittently moving said pre-settable means; and means along each path of movement of said member for controlling the starting and stopping of said member therealong, said means including separate means responsive to each movement of the member along said paths for determining when said separate source of power is to be rendered effective.

35. In an apparatus for producing a relatively large number of functions, a control member including a plurality of portions, each adapted selectively to be set for causing said apparatus to produce any function of which it is capable; means for moving said control member so that successive of said portions become effective; means adapted to respond to each of said functions at any time during said functions for rendering effective said moving means, said responsive means including a plurality of portions, one for each of said control-member portions; and means for maintaining all of said portions in exact phase relation at all times.

36. Variable-cycle apparatus comprising in combination, a member adapted to be moved in either direction along a path at a plurality of speeds a substantially great number of times within a cycle of operation; means for moving said member; a control member including specific portions adapted adjustably to support means for selectively controlling said member-moving means for each movement of said member within said cycle; means for controlling the effectiveness of said control member including a portion for each specific portion of said control

member adapted adjustably to support means for cooperating with means, movable in proportion to the movement of said member, at any point along its path of travel for controlling said control member; and means for maintaining said portions in exact phase relation at all times.

37. Apparatus comprising in combination, a member adapted to be moved in either direction along a path at any one of a plurality of speeds; 10 means for moving said member along said path; a control member including a plurality of portions, each adapted selectively to be set for controlling said member-moving means; means responsive to each movement of said member at any point along its path of travel for controlling the starting, stopping and duration of the next succeeding movement of said member including a plurality of portions, one for each of said control-member portions; and means for maintaining all of said portions in exact phase relation at all times.

38. Apparatus comprising in combination, a member adapted to be moved in either direction along a plurality of paths at a plurality of speeds; 25 means for moving said member along said paths; a common control member including a plurality of portions, each adapted selectively to be set for controlling said member-moving means; separate means for each path along which said member is adapted to be moved for controlling the starting, stopping and duration of motion of said member along said path, each of said separate means including a plurality of portions, one for each of said control-member portions; and 30 means for maintaining all of said portions in exact phase relation at all times.

39. Apparatus comprising in combination, a plurality of appliances each adapted to produce a relatively large number of functions; a control 40 member for each of said appliances having a plurality of portions, each adapted selectively to be set for causing its appliance to produce any function of which it is capable; means for moving each of said control members so that successive 45 of said portions become effective; means associated with each appliance adapted to respond to each of its functions at any time during said functions for rendering effective the moving means of its control member, said responsive 50 means including a plurality of portions, one for each of its control member portions; means for maintaining all of the portions for each appliance severally in exact phase relation at all times; and means associated with each of said 55 control members for rendering effective the control member of the other appliances.

40. Apparatus comprising in combination, a member; means for moving said member in either direction along a plurality of paths at a plurality of speeds; adjustable means adapted to be pre-set for controlling said member-moving means for determining the path, direction and rate of motion of said member; means for each path of movement of said member including separate adjustable means responsive to the movement of said member throughout its entire path of travel for controlling the starting and stopping of each motion of said member; and means for operating said pre-settable means.

41. Apparatus comprising in combination, a plurality of appliances each including a member adapted to be moved along separate paths at a plurality of speeds; means associated with each of said appliances and adapted to be pre-set for independently selecting the path, direction and

rate of movement of its member; power-operated means associated with each appliance for operating its pre-settable means; and means associated with each of said appliances for initiating the activity of any of said power-operated means in response to a position any of said members may assume along their respective paths.

42. In an apparatus for producing a relatively large number of functions, control means including a plurality of portions, each adapted selectively to be set for causing said apparatus to produce any function of which it is capable; means adapted successively to render effective said portions; means adapted to respond to each of said functions at any time during said functions including a plurality of portions, one for each of said control-means portions, each adapted adjustably to be pre-set for initiating the activity of the means that renders said control-means portions effective; and means for main-

taining all of said portions in exact phase relation at all times.

43. Apparatus comprising in combination, a member; means for moving said member along a path; a control for said member-moving means for causing said member to move a plurality of times along said path for different overlapping distances within a cycle of operation, said control including means having a plurality of portions each adapted adjustably to be pre-set to effect the movement of said member in either direction along said path; means including a plurality of portions, one for each of said control-means portions, each of which is adapted adjustably to be pre-set to terminate a movement of said member at any point along said path; and means for maintaining all of said portions in exact phase relation.

EDWARD P. BULLARD, III.
